UNITED STATES PATENT OFFICE.

EMIL G. SAUER, OF RICHMOND HILL, NEW YORK, ASSIGNOR TO BIGELOW CARPET COMPANY, A CORPORATION OF MASSACHUSETTS.

DESIGN FOR A RUG.

40,926.

Specification for Design. Patented Sept. 27, 1910.

Application filed August 11, 1910. Serial No. 576,777. Term of patent 7 years.

To all whom it may concern:

Be it known that I, EMIL G. SAUER, a citizen of the United States, residing at Richmond Hill, in the county of Queens and State of New York, have invented a new, original, and ornamental Design for a Rug, of which the following is a specification, reference being had to the accompanying drawing, forming part thereof.

The design, as shown in the drawing, consists in a new design for a rug, one quarter of the full design being shown in the drawing.

The design comprises a medallion in center and one at end placed on a covered ground work, with border as shown in the drawing.

I claim:

The ornamental design for a rug, as shown, and described.

EMIL G. SAUER.
